UNITED STATES PATENT OFFICE

125,256

DESIGN FOR A VENDING MACHINE CABINET

Edgar N. Colson, Kansas City, Mo., assignor to C. Earl Hovey, Kansas City, Mo., as trustee

Application November 16, 1940, Serial No. 96,636

Term of patent 14 years

To all whom it may concern:

Be it known that I, Edgar N. Colson, a citizen of the United States, residing at Kansas City, in the county of Jackson and State of Missouri, have invented a new, original, and ornamental Design for a Vending Machine Cabinet, of which the following is a specification, reference being had to the accompanying drawing, forming a part thereof.

Fig. 1 is a perspective view of the vending machine cabinet, showing my design.

Fig. 2 is a front elevational view thereof; and Fig. 3 is a side elevational view thereof.

I claim:

The ornamental design for a vending machine cabinet, as shown.

EDGAR N. COLSON.
